UNITED STATES PATENT OFFICE.

LOUIS STERN, OF WOODMERE, NEW YORK, ASSIGNOR TO THE DE LUXE CLOCK & MFG. CO., INC., OF NEW YORK, N. Y., A CORPORATION OF NEW YORK.

CLOCK CRYSTAL.

Application filed December 13, 1927. Serial No. 239,657.

The main objects of the present invention are to provide a clock crystal which is substantially non-breakable, which is inexpensive to manufacture, which may be easily and securely fastened in position, which does not require any high degree of accuracy as to dimensions or the forming of any bezel engaging edge, and which may be employed as a close-fitting cover for such parts of the 10 clock face as may be present outside of the clock dial.

In carrying out my invention I preferably form the crystal of celluloid or any other similar transparent substantially non-breakable and inexpensive material. The crystal is provided with a center portion which may conform in shape to the shape of the dial and which is spaced from the dial to a distance sufficient to permit the free movement 20 of the hands. In a separate plane from this center portion is an annular marginal or peripheral portion which may be clamped or otherwise rigidly secured directly to or in direct contact with a corresponding portion 25 of the clock face outside of the dial. Between this center portion and the outer or marginal portion is a wall integral with both of said portions and serving to connect and space them to the desired distance. This 30 wall preferably follows the contour of the dial and holds the center portion of the crystal at a distance above the dial to permit the movement of the hands.

In the accompanying drawings I have 35 illustrated certain embodiments of my invention, but it will of course be understood that various other forms may be designed within the scope of my invention, particularly so far as concerns the forming of the crystal 40 in accordance with the relative shapes and sizes of the clock face and dial thereon.

In these drawings:

Fig. 1 is a front view of a clock having a crystal constructed in accordance with my 45 invention;

Fig. 2 is a side elevation, the front portion of the clock case being in section;

Fig. 3 is a front view showing another form;

Fig. 4 is a central longitudinal section;

Fig. 5 is a perspective view of the crystal known in Figs. 3 and 4;

Fig. 6 is a front view of a third form; and

Fig. 7 is a section through the form shown 55 in Fig. 6.

In the construction shown in Figs. 1 and 2, the works of the clock are mounted in a casing 10 which is secured to the rear side of a front wall which may be of metal or 60 any other suitable material. The lower portion of this wall serves as a supporting bracket 11, while the front of the body portion 12 has printed, embossed or otherwise formed thereon the annular row of numerals forming the clock dial. These numerals are shown as being formed on an annular raised portion 13. The arbor of the clock projects through the center of the dial and the hands 14 are mounted on the front of the arbor 70 and in proper position in respect to the dial.

In my improved construction there is provided a crystal of celluloid or any similar transparent non-breakable material. This includes a center portion 15 of substantially 75 the same diameter as the numeral bearing portion 13 constituting the clock dial. This center portion may be either flat or slightly convex as desired. Around the periphery of this center portion 15 is a wall 16 which is 80 of substantially cylindrical form and which serves to space the center portion 15 to the desired distance from the clock face. The inner edge of the wall 16 is formed integral with a flat marginal portion 17 which 85 lies in close contact with the clock face outside of the dial. This outer marginal portion lies in a plane substantially parallel to the plane of the center portion 15, but is spaced therefrom to a distance dependent 90 upon the height of the wall 16. This marginal portion is secured directly to the clock face by any suitable form of clamping means. As shown, there is an annular clamping member 18 which may be made of an internal diameter substantially equal to the diameter 95 of the wall 16 and an external diameter substantially equal to the outside diameter of the marginal portion 17 of the crystal.

This annular member 18 may have any suitable form of ornamentation embossed or otherwise formed thereon. The clamping screws 19 may go directly through this annular member and through the marginal portion 17 into the clock face so as to secure the three 100 parts together.

In Figs. 3, 4 and 5 I have shown a construction in which the casing 10^a for the

works is of the usual cylindrical form with the front wall 12^a secured thereto and carrying the dial. This wall 12^a is shown as being circular and of the same diameter as the casting 10^a, whereas the dial is shown as substantially square. In this arrangement the center portion 15^a of the crystal may also be substantially square while the face as a whole is circular. The flat annular portion 17^a encircling the dial is secured to the clock face by screws 19^a. The casing with the crystal secured thereto may be mounted in any suitable form of clock case which will cover all portions of the clock face except the dial. Merely for purposes of illustration I have shown a rectangular clock case 20 having a cylindrical opening in the rear into which the works casing 10^a may be inserted. The front wall of the clock case has an aperture 21 which is substantially square and encircling this is an inwardly extending wall 22 against which the portion of the clock face and crystal outside of the dial may engage. The annular wall 16^a which encircles the center or dial covering portion 15^a may be of a height either lesser or greater than the thickness of the wall 22 depending upon the nature and material of the clock case 20.

Although it is preferable that the center portion of the crystal be of a form corresponding to that of the dial, it is not essential so far as my particular invention is concerned.

In Figs. 6 and 7 I have shown a wall 12^b which may constitute the clock face and secured to or form a part of any suitable clock case. It has a central aperture for the main hand carrying arbor. This clock face is shown as substantially square, while the dial 12^b is shown of octagon shape. The crystal has a center portion 15^b which may be either square or octagonal, but is shown as square. The peripheral wall 16^b spaces this center portion above the clock face, while the marginal portion 17^b is made comparatively narrow and may be secured directly to the clock face by the screws 19^b at the corners.

In each of the forms illustrated the wall 16, 16^a, or 16^b serves to define the spacing of the center of the crystal above the clock face. This is a continuous wall extending around the dial. In describing it as "annular" I do not use that term as limiting the wall to a circular one but include within the term also a wall following an elliptical, square, hexagonal, or any other desired form or shape of dial or clock face. In the same way the wall 17, 17^a, or 17^b directly contacts with the clock face and may be considered as annular even though it may have other than circular inner and outer edges and may be variable in width, as for instance as shown in Fig. 5.

The walls 17, 17^a and 17^b preferably directly contact with the clock face, but this is not essential for they may be secured closely adjacent to the clock face, but not directly thereto. The annular wall 16, 16^a, or 16^b may extend substantially at right angles to the plane of the clock face, but preferably merges into the center and marginal portions by curved intermediate portions which facilitate the moulding of the crystal. Obviously this connecting and spacing wall between the center and margin might be inclined, that is disposed at any desired angle other than a right angle to the clock face.

In using the term "celluloid" I do not wish to be restricted to any particular composition or material as there are various analogous materials which are substantially non-breakable and sufficiently transparent for the present invention. I desire to include all such equivalents of celluloid under that term.

Having thus described my invention what I claim as new and desire to secure by Letters Patent is:

1. In combination a clock face having a dial and a substantially flat annular portion encircling the dial, a sheet of non-breakable transparent material having a center portion serving as a crystal and corresponding in shape to, but spaced from said dial, a marginal portion substantially parallel to and in direct contact with said annular portion of said clock face, and an integral connecting wall for supporting said center portion and holding it in spaced relationship to said clock face, and fastening members extending through said marginal portion for securing the latter to the annular portion of said clock face.

2. In combination a clock face having a dial, a crystal having a center portion, a peripheral wall and a marginal portion, said marginal portion being substantially parallel to and spaced from said center portion by said wall, and means for securing said marginal portion directly to said clock face outside of said dial.

3. In combination a clock face having a dial, a crystal having a center portion, a peripheral wall and a marginal portion, said marginal portion being substantially parallel to and spaced from said center portion by said walls, means for securing said marginal portion directly to said clock face outside of said dial, and an annular wall in front of and concealing said marginal portion and having its inner edge disposed closely adjacent to the peripheral wall of said crystal.

Signed at 1107 Broadway in the county of New York, and State of New York, this 10th day of December, 1927.

LOUIS STERN.
